United States Patent Office

Des. 218,696
Patented Sept. 15, 1970

218,696

TOY VEHICLE

Robert Thomas Auer, Laurie Jay Campbell, and Calvin S. Cook, Erie, Pa., assignors to Louis Marx & Co., Inc., New York, N.Y., a corporation of New York

Filed Feb. 16, 1970, Ser. No. 21,447

Term of patent 14 years

Int. Cl. D21—02

U.S. Cl. D34—15

FIG. 2

FIG. 3

FIG. 4

FIG. 1 is a front and right side perspective view of a toy vehicle embodying our new design assembled with wheels;

FIG. 2 is a left side elevational view thereof;

FIG. 3 is a rear elevational view thereof;

FIG. 4 is a perspective view similar to FIG. 1 but showing the toy vehicle of the instant invention assembled with ski-like runners to permit the vehicle to travel on snow and ice.

We claim:

The ornamental design for a toy vehicle, as shown and described.
